UNITED STATES PATENT OFFICE.

SERENUS M. COLBURN, OF MINNEAPOLIS, MINNESOTA, ASSIGNOR OF ONE-HALF TO
FREDERICK KEEES, OF MINNEAPOLIS, MINNESOTA.

DESIGN FOR A STREET-LIGHT STANDARD.

44,054.

Specification for Design.

Patented May 20, 1913.

Application filed March 17, 1913. Serial No. 755,041. Term of patent 7 years.

To all whom it may concern:

Be it known that I, SERENUS M. COLBURN, a citizen of the United States, residing at Minneapolis, in the county of Hennepin and State of Minnesota, have invented a new, original, and ornamental Design for a Street-Light Standard, of which the following is a specification, reference being had to the accompanying drawings, forming part thereof.

Figure 1 is a view in elevation showing a

street light standard, embodying the improved design; and Fig. 2 is a plan view of the same.

I claim:

The ornamental design for a street light standard, as shown.

SERENUS M. COLBURN.

In the presence of—

F. D. MERCHANT,
HARRY D. KILGORE.
